(57) **CLAIM**

The ornamental design for a punch down tool, as shown and described.

DESCRIPTION

FIG. 1 is a perspective view of a punch down tool having the inventive design;

FIG. 2 is a left side view of the punch down tool shown in FIG. 1;

FIG. 3 is a right side view of the punch down tool shown in FIG. 1;

FIG. 4 is a top view of the punch down tool shown in FIG. 1;

FIG. 5 is a bottom side view of the punch down tool shown in FIG. 1;

FIG. 6 is a front side view of the punch down tool shown in FIG. 1; and,

FIG. 7 is a back view of the punch down tool shown in FIG. 1.

The broken lines in the drawings are for the purpose of illustrating portions of the punch down tool that form no part of the claimed design.
